DUPLEX STEAM CONDENSER

Jack Fanning, Atlanta, Ga.

Application February 1, 1950, Serial No. 141,669

6 Claims. (Cl. 261—11)

1

This invention relates to a duplex steam condenser and more particularly to the construction and arrangement of a steam condensing unit utilizing circulating water for cooling.

In devices which operate by steam, such as steam engines and steam presses, it is particularly advantageous to collect the steam after use and condense it for re-use in the boiler, since this saves the expense of wasted water; and, further, it is desirable to maintain the collected boiler feed water at as high a degree of temperature as possible, since this saves the expense of fuel for reheating the water in the boiler; and, in collecting the used steam from the particular device, all foreign substances, such as emulsified oil, must be removed before the water is re-introduced into the boiler.

Various prior art condensers have been developed for use in conjunction with steam generating systems, but they have been impractical from important standpoints, such as expensiveness in initial purchase or heavy maintenance during continuous operation due to their failure to withstand the large changes in pressure and temperature involved in condensing steam.

An object of this invention is to provide a condenser which is constructed and arranged to withstand the changes in pressure and temperature involved in condensing steam.

Another object of this invention is to provide a condenser which effectively separates emulsified substances from the steam.

A further object of this invention resides in the particular construction whereby the condensate is maintained at a high degree of temperature.

Also an object of this invention is to provide a condenser which is inexpensive to fabricate and market.

Another object of this invention is to provide a condenser which may be readily utilized with all types of steam systems.

An additional object of this invention is to provide a condenser which is safe and economical to maintain and operate.

Other and further objects and advantages of my invention will be apparent from the following description taken in conjunction with the accompanying drawings in which like characters of reference designate corresponding parts throughout the several views, and wherein:

Fig. 1 is a top view, partly in cross-section, of an embodiment of my invention.

Fig. 2 is a cross-sectional view taken on the line 2—2 of Fig. 1.

Fig. 3 is a cross-sectional view taken on the line 3—3 of Fig. 1.

In the embodiment of my invention chosen for illustration, an inlet pipe 10 has a bifurcated portion forming a pair of parallel condenser

2

tubes 11, 11' which after a continuation rejoin or come together to form an outlet pipe 12 which connects to a condensate header pipe 13. The header pipe 13 in turn feeds into smaller header tubes 14 which in turn feed into an auxiliary header pipe 15 from which the condensate would empty into the conventional skim tank or sump.

Each of the condenser tubes 11, 11' is jacketed or surrounded by cooling water jackets 16, 16', respectively, which form an enclosed casing around the condenser tubes 11, 11'. The cooling jackets 16, 16' are provided with input pipe lines 17, 17' for receiving cooling liquid near the junction at outlet pipe 12, and output pipe lines 18, 18' for drawing the heated cooling water off near the input tube 10. The input lines 17, 17' and the output lines 18, 18' may be connected to any suitable continuous cooling water system which pumps the cooling water in at a point near the outlet pipe 12 and out at a point near the inlet pipe 10.

Intermediate the length of the condenser tubes 11, 11' are pairs of spaced apart internal straightening vanes 19, 19' and 20, 20', each of which, as is readily seen in Fig. 2, comprises blades or baffles arranged in 90° sectors, and the function of these vanes will be subsequently described. Also located internally of each of the condenser tubes 11, 11' are expansion orifices 21, 21', each being placed beyond the straightening vanes 19, 19', respectively, the junction at which the tubes 11, 11' join outlet pipe 12.

Spray chambers 22, 22' are formed at the crotch or intersecting portion of the condenser tubes 11, 11' near the input tube 10 and the outlet tube 12, respectively, and spray chambers 22, 22' house spray nozzles 23, 23', respectively, which are provided with a cool liquid through a common pipe line 24.

In the operation of my duplex steam condenser, steam from the exhaust side of the particular apparatus being operated moves by its own energy through the inlet pipe 10 reaching the bifurcated portion or crotch formed by the branching off of the tubes 11, 11'; and as the steam divides off into the tubes 11, 11' it receives a small amount of cold water sprayed from the nozzle 23. Passing on through the separate condenser tubes 11, 11' the steam is continuously being cooled by the cooling water inside the jackets 16, 16' circulating in the opposite direction from the movement of the steam.

As the steam contacts the first set of straightening vanes 19, 20, the turbulence is decreased, and the steam proceeds on through to the second set of straightening vanes 19', 20' which further reduce the turbulence. Then the steam proceeds through the expansion orifices 21, 21' into the second crotch portion where it receives a small spray of cool liquid from the nozzle 23'. Finally

the steam enters the output tube 12 and from there goes into the header pipe 13, through the submerged tubes 14, into the auxiliary header pipe 15, emerging as hot water which is collected in an ordinary skim or sump tank for re-introduction as boiler feed water.

By the addition of cold water through the nozzles 23, 23', any emulsified substance, such as oil or the like, in the steam is turned back into its natural state and is deposited in the skim tank in that form; and the added quantity of water causes the skim tank to have a slight overflow at all times, and this overflow carries with it the undesirable oil slick, thereby preventing any re-introduction into the boiler.

In my new and novel duplex steam condenser, the temperature, velocity, and pressure of the steam are reduced gradually rather than all at once. The two branches or duplex tubes 11, 11' separate the steam for cooling, and the action of the two pairs of straightening vanes 19, 19' and 20, 20' along with the expansion orifices 21, 21' successively reduce the turbulence and give better cooling efficiency with less noise. This arrangement also provides a careful equality of pressures which assures a condenser of longer life.

Moreover, the use of my invention does not create any back-pressure on the apparatus, but in fact reduces the pressure and affords greater operating efficiency for the machine.

It will be obvious to those skilled in the art that many modifications and changes may be made in the embodiment of my invention shown and described without departing from the scope of my invention as defined in the appended claims.

I claim:

1. In apparatus of the class described, an inlet pipe, an outlet pipe, a plurality of pipes branching from said inlet pipe and said outlet pipe and forming crotches therebetween, a spray chamber communicating with one of said crotches, condenser tubes interconnecting the pipes branching from said inlet pipe with the pipes branching from said outlet pipe, jackets for coolant surrounding said condenser tubes, means for circulating a coolant through said jackets, and means in said spray chamber for spraying fluid into steam passing through said apparatus substantially at the crotch with which said spray chamber communicates.

2. In apparatus of the class described, an inlet pipe, an outlet pipe, a plurality of pipes branching from said inlet pipe and said outlet pipe and forming crotches therebetween, spray chambers communicating respectively with each said crotch, condenser tubes interconnecting the pipes branching from said inlet pipe with the pipes branching from said outlet pipe, jackets for coolant surrounding said condenser tubes, straightening vanes inside said condenser tubes, an expansion orifice in each condenser tube, means for circulating a coolant through said jackets, and means in said spray chambers for spraying fluid into steam passing through said apparatus substantially at said crotches.

3. In apparatus of the class described, an inlet pipe, an outlet pipe, a plurality of pipes branching from said inlet pipe and said outlet pipe at angles of approximately 45° and forming crotches therebetween, spray chambers communicating respectively with each said crotch, condenser tubes interconnecting the pipes branching from said inlet pipe with the pipes branching from said outlet pipe, jackets for coolant surrounding said con-

denser tubes, straightening vanes inside said condenser tubes; an expansion orifice in each condenser tube, means for circulating a coolant through said jackets, and means in said spray chambers for spraying fluid into steam passing through said apparatus.

4. In apparatus of the class described, an inlet pipe, an outlet pipe, a plurality of pipes branching from said inlet pipe and said outlet pipe at angles of approximately 45° and forming crotches therebetween, spray chambers communicating respectively with each said crotch, condenser tubes interconnecting the pipes branching from said inlet pipe with the pipes branching from said out-

15 let pipe, jackets for coolant surrounding said condenser tubes, straightening vanes inside said condenser tubes, an expansion orifice in each condenser tube between said straightening vanes and said outlet pipe, means for circulating a coolant
20 through said jackets, and means in said spray chambers for spraying fluid into steam passing through said apparatus.

5. In apparatus of the class described, an inlet pipe, an outlet pipe, a plurality of pipes branching from said inlet pipe and said outlet pipe at angles of approximately 45° and forming crotches therebetween, spray chambers communicating respectively with each said crotch, condenser tubes interconnecting the pipes branching from said inlet pipe with the pipes branching from

35 said outlet pipe, jackets for coolant surrounding said condenser tubes, straightening vanes inside each condenser tube and spaced along the length thereof, an expansion orifice in each condenser tube between said straightening vanes and said outlet pipe, means for circulating a coolant through said jackets, and means in said spray chambers for spraying fluid into steam passing through said apparatus.

40 6. In apparatus of the class described, an inlet pipe, an outlet pipe, a plurality of pipes branching from said inlet pipe and said outlet pipe at angles of approximately 45° and forming crotches therebetween, spray chambers aligned with inlet pipe and said outlet pipe and communicating respectively with each said crotch, condenser tubes interconnecting the pipes branching from said inlet pipe with the pipes branching from said outlet pipe, jackets for coolant surrounding said condenser tubes, straightening vanes inside each condenser tube and spaced along the length thereof, an expansion orifice in each condenser tube between said straightening vanes and said outlet pipe, means for circulating a coolant through said jackets, and means in said spray chambers for spraying fluid into steam passing through said apparatus.
